INVENTOR

BY *Victor J. Evans.*

ATTORNEY

WITNESS:

UNITED STATES PATENT OFFICE.

JOHN V. BUTTS, OF SANDERS, KENTUCKY.

WRENCH.

Application filed March 18, 1924. Serial No. 700,116.

To all whom it may concern:

Be it known that I, JOHN V. BUTTS, a citizen of the United States, residing at Sanders, in the county of Carroll and State 5 of Kentucky, have invented new and useful Improvements in Wrenches, of which the following is a specification.

This invention relates to wrenches and has for an object the provision of a wrench of 10 simple and durable construction which is capable of rapid adjustment and which will be securely held in adjusted position.

More specifically stated, the invention provides a wrench which includes a rigid jaw 15 and a relatively movable jaw which is adjustable upon the shank of the rigid jaw, with means carried by the movable jaw whereby the latter may be adjusted and held in adjusted position, the said means including an inner sleeve which carries the movable jaw and an outer sleeve which may be operated to hold the movable jaw in adjusted position, the holding means also acting to retain the outer sleeve upon the inner sleeve. 20

With the above and other objects in view, the invention further includes the following novel features and details of construction, to be hereinafter more fully described, illustrated in the accompanying drawings and 25 pointed out in the appended claim.

In the drawings:—

Figure 1 is an elevation of a wrench constructed in accordance with the invention.

Figure 2 is an edge view of the same.

Figure 3 is an elevation looking at the reverse side from that shown in Figure 1.

Figure 4 is a transverse section on the line 4—4 of Figure 2.

Figure 5 is a detail section taken diametrically through the outer sleeve.

Referring to the drawings in detail, the reference character 10 indicates the shank of the improved wrench which is provided at one end with a handle or grip 11 and at its 45 opposite end with a jaw 12 which is rigid with the shank. The opposite sides of the shank are longitudinally recessed as shown at 13, the recess upon one side of the shank opening into one edge, while the recess upon the opposite side of the shank opens into the opposite edge so that the said recesses are relatively offset. Extending from opposite sides of the shank are spaced projections or 50 teeth 14, the latter extending from the inner

edges of the recesses 13, so that the teeth 55 upon one side of the shank are offset with respect to the teeth upon the opposite side of said shank, the relative positions of the teeth 14 and the recesses 13 being clearly shown in Figure 4 of the drawings. 60

Slidably mounted upon the shank 13 is a sleeve 15, which may be hereinafter referred to as the inner sleeve, the said sleeve having extending from one end thereof a jaw 16. The sleeve 15 is mounted for sliding movement along the shank and for this purpose is provided with grooves 17 which receive opposite edges of said shank and by sliding the sleeve, the jaw 16 may be adjusted with respect to the jaw 12, as will be readily 70 understood.

Rotatably mounted upon the inner sleeve 15 is an outer sleeve 18 whose outer periphery is preferably knurled or serrated as shown. This outer sleeve carries inwardly extending 75 oppositely disposed projections or lugs 19 which are adapted to pass through openings or slots 20 provided in the inner sleeve 15 upon diametrically opposite sides thereof. The lugs 19 are adapted to engage the spaced 80 teeth 14 to hold the movable jaw 16 in adjusted position. By rotating the outer sleeve 18, the lugs 19 may be disengaged from the teeth 14 and rapid adjustment of the movable jaw effected. 85

The outer periphery of the inner sleeve 15 is provided with oppositely disposed spaced recesses 21, while secured within the outer sleeve 18 are oppositely located spring arms or fingers 22 which are provided with offset portions for engagement with the walls of the notches 21. The notches are so spaced as to receive the offset portion of the spring 90 22 when the movable jaw 16 is in either locked or released position so that the sleeve 18 will be held against accidental rotation. 95

The invention is susceptible of various changes in its form, proportions and minor details of construction and the right is herein reserved to make such changes as properly fall within the scope of the appended claim. 100

Having described the invention what is claimed is:—

A wrench comprising a shank having longitudinally disposed relatively offset recesses in opposite sides thereof, rows of spaced teeth extending downwardly and longitudi- 105

dinally with the shank from opposite sides of an integral jaw adjacent the recesses, a transversely slotted inner sleeve having opposed guide grooves and slidably receiving the opposite edges of the shank therein, a movable jaw carried by the inner sleeve, an outer rotatable sleeve received on the inner sleeve and having inwardly extending

oppositely disposed lugs received in the slots and interposed between the teeth, and 10 spring means included in the rotatable sleeve for engagement with the inner sleeve to hold the same against accidental displacement.

In testimony whereof I affix my signature.

JOHN V. BUTTS.
